UNITED STATES PATENT OFFICE.

GEORGE H. DORGELOH, OF SCHENECTADY, NEW YORK, ASSIGNOR TO GENERAL ELECTRIC COMPANY, A CORPORATION OF NEW YORK.

RHEOSTAT.

No. 894,614.

Specification of Letters Patent. Patented July 28, 1908.

Application filed January 11, 1908. Serial No. 410,322.

To all whom it may concern:

Be it known that I, GEORGE H. DORGELOH, a subject of the Emperor of Germany, residing at Schenectady, in the county of Schenectady, State of New York, have invented certain new and useful Improvements in Rheostats, of which the following is a specification.

This invention relates to devices for controlling electric motor circuits and has for its object the provision of a device of this character in which the starting and speed regulating of the motor will be accomplished in a simple and efficient manner.

In carrying out my invention I provide in connection with starting and speed regulating resistances a pair of controlling arms, one for each resistance. These arms are arranged so as to operate independently of each other to vary the resistances. The arms are preferably concentrically pivoted and the construction and arrangement is such that the field control arm is mechanically locked against movement until the starting arm is moved to running or short-circuited position. The arms are so interlocked that upon failure of voltage the starting arm will return to the off position and carry with it the field control arm.

In the accompanying drawing in which I have shown my invention embodied in concrete mechanism, Figure 1 is a plan view of the device showing the circuit connections and Fig. 2 is a side elevation of the controlling mechanism.

Referring to the drawing, 10 is an insulating base of slate or soapstone provided with a series of studs 11 forming the terminals of starting resistance 12 and a series of studs 13 similarly connected to a speed controlling resistance 14. The studs 11 and 13 are preferably concentrically arranged as shown and are adapted to be engaged by the controlling arms 15 and 16 respectively. The controlling arm 15 which engages the studs 11 is biased to the off position by means of a spring 17 and is arranged to be held in running position in the usual way by means of the no-voltage magnet 18. This arm 15 is operated independently of the arm 16 by means of the handle 19. The arm 16 is pivoted upon the stud 20 and is moved independently of the arm 15 to engage the studs 14 by means of the handle 21. The hub 22 of this arm is cut away to form a notch 23, which is adapted to be engaged by a latch or pawl 24 to lock the

same in the starting position shown in Fig. 1. This latch is spring-pressed into the notch and is provided with a pin 25 which projects upwardly in the path of the arm 15. When this latter arm engages the pin 25, it forces the pawl out of the notch 23 and releases the arm 16.

The arrangement of circuits and the mode of operation are as follows: The resistance 14 is preferably connected in the field circuit 65 of the motor while the starting resistance 12 is in the armature circuit in the usual way. To start the motor the line switch 26 being closed, the arm 15 is first moved to the right to cut out starting resistance 12, current 70 passing from the positive main to the arm 15, resistance 12, armature A and back to line. When the arm reaches short-circuiting or running position, it engages the pin 25 and releases the arm 16. It is then held in running position by the no-voltage magnet 18. The arm 16 is now free to be moved to insert resistance 14 in the circuit of the field F of the motor to increase its speed. The arm 16 may be left upon any of the studs 14 as desired. Upon failure of voltage the arm 15 80 will return to the starting position and carry with it the arm 16 so that the motor will always be started at maximum field strength.

While I have described my invention as 85 embodying certain structural features and circuit arrangement, it should be understood that I do not limit my invention in these particulars except in so far as it is limited by the scope of the claims annexed hereto.

What I claim as new and desire to secure by Letters Patent of the United States, is

1. A motor starting and speed regulating rheostat comprising an armature resistance and a field resistance, pivoted controlling 95 members arranged to move independently of each other to vary said resistances, and means for preventing movement of the field control member until the armature control member reaches short-circuited position. 100

2. A motor starting and speed regulating rheostat comprising a field resistance and a controlling arm therefor, a starting resistance having a controlling arm biased to off position and movable independently of said field 105 arm to vary its resistance, and means for preventing movement of the field arm until the starting arm reaches running position.

3. A motor starting and speed regulating rheostat comprising a starting resistance and 110

2. A speed regulating resistance, concentrically pivoted controlling arms arranged to move independently of each other to vary said resistances, and means for preventing movement of the speed regulating arm until the starting arm reaches running position.

4. A motor starting and speed regulating rheostat comprising a starting resistance and a speed regulating resistance, concentrically pivoted controlling arms arranged to move independently of each other over the same path to vary said resistances, and means for preventing movement of the speed regulating member until the starting arm reaches running position.

5. A motor starting and speed regulating rheostat comprising a starting resistance and a speed regulating resistance, concentrically pivoted controlling arms arranged to move independently of each other to vary said resistances, and means for mechanically locking the speed regulating arm against movement until the starting arm reaches running position.

6. A motor starting and speed regulating rheostat comprising a field resistance and a controlling arm therefor, a starting resistance having the control arm biased to the off position, and movable independently of said arm to vary its resistance, means for preventing movement of the field arm until the starting arm reaches running position, and means whereby the field arm is moved by the starting arm when the latter returns in response to its bias.

7. A motor starting and speed regulating rheostat comprising an armature resistance and a controlling arm therefor, movable in

one direction to cut out said resistance, a field resistance and a controlling arm movable in the same direction and over the same path to insert said resistance, and means for preventing movement of the field control arm until the starting arm reaches short-circuited position.

8. A motor starting and speed regulating rheostat, comprising an armature resistance and a field resistance, concentrically pivoted controlling arms mounted for independent movement over the same path to vary said resistances, connections whereby said arms are movable in opposite directions to insert resistance and means for mechanically locking one of said arms against movement until the other arm reaches a predetermined position.

9. A motor control rheostat, comprising an armature control mechanism provided with no-voltage release features, and a field control mechanism movable independently of each other in opposite directions and over the same path to insert resistance, means for interlocking the said mechanisms whereby the field control mechanism will be returned with the armature control mechanism upon failure of voltage, and means for mechanically locking the field control mechanism against movement until the armature control mechanism has reached running position.

In witness whereof, I have hereunto set my hand this 9th day of January, 1908.

GEORGE H. DORGELOH.
